CLAIM

The ornamental design for a mixer, as shown and described.

DESCRIPTION

1. Mixer

1.1 is a perspective view showing the mixer of my design;
1.2 is a front elevational view thereof;
1.3 is a rear elevational view thereof;
1.4 is a right side elevational view thereof;
1.5 is a left side elevational view thereof;
1.6 is a top plan view thereof; and
1.7 is a bottom plan view thereof.

The portions of the mixer shown in broken lines are included
for the purpose of illustrating unclaimed portions of the
mixer and form no part of the claimed design.

1 Claim, 6 Drawing Sheets
